ORNAMENTAL METAL-WORK PANEL

Leonard M. Logan III, Fort Worth, Tex., assignor to
McKinley Iron Works, Fort Worth, Tex., a partnership
composed of George C. Kemble, John B. Lloyd, and
Ivan Greene, trustee for Judith and Dean McKinley

Application February 24, 1959, Serial No. 54,722

Term of patent 14 years

(Cl. D54—2)

FIG. 1

FIG. 2

FIG. 3

Fig. 1 is an elevation of one side of an ornamental metal-work panel embodying my new design;

Fig. 2 is an edge view looking toward the left hand edge of Fig. 1;

Fig. 3 is a top view; and

Fig. 4 is an elevation of the opposite side of the panel.

I claim:

The ornamental design for an ornamental metal-work panel, as shown.
